UNITED STATES PATENT OFFICE.

CHARLES TORRES WEYMANN, OF PARIS, FRANCE, ASSIGNOR TO SOCIÉTÉ DES ÉTABLISSEMENTS ED. JAEGER, OF PARIS, FRANCE.

ZERO-SETTING DEVICE FOR REGISTERS.

Application filed April 4, 1922. Serial No. 49,514.

To all whom it may concern:

Be it known that I, CHARLES TORRES WEYMANN, a citizen of the French Republic, residing in Paris, France, have invented 5 new and useful Improvements in the Manufacture of Zero-Setting Devices for Registers, of which the following is the specification.

It is known that in zero setting devices 10 for registers, each of the drums is integral with a ratchet wheel having ten teeth and carries on its opposite face corresponding to the juxtaposed drum representing the units of higher order, a detent subjected 15 to the action of a spring. This detent rests on the outer part of the circular disc which is interposed between two adjacent drums and is provided with a transfer notch. This disc is integral with the fixed axis 20 on which the whole of the drums is mounted and its notch allows the detent to actuate the drum of higher units during $\frac{1}{10}$ of a revolution.

The present invention has for its object 25 improvements in the manufacture of zero setting devices for registers, the improvements having more particularly for its object to effect the zero setting of the drum by returning to their initial relative starting positions the parts which actuate them and render them integral with each other. For this purpose, use is made of a comb the branches of which in the shape of pawls 30 respectively act on the teeth of the ratchets carried by the drums, a portion of one of the teeth being removed on the set of teeth of each of these ratchets so that it will not be actuated by the corresponding pawl when the driving parts and its drum have 35 returned to their starting positions.

In the diagrammatic drawing and by way of example:

Fig. 1 illustrates in vertical section an indicator made in accordance with the improvements forming the subject matter of the present invention.

Fig. 2 shows partly in elevation, partly in vertical section the arrangement of the drums bearing the digits and the parts 50 actuating them.

Fig. 3 is a corresponding plan view there- 55 of showing the operating parts for zero setting.

Referring now, more particularly, to the accompanying drawing there is pro-

vided a main shaft A for supporting a plurality of digit bearing drums a, the latter being each fitted interiorly with a spring controlled claw or finger a' which coacts with the adjacent notched transfer disc b' 60 for effecting step rotation of the drums.

As intimated in the foregoing, the improvements forming the subject matter of the present invention are more specially intended to effect the zero setting of the drums a of the register by acting, not directly on the said drums, but on the parts which drive them for their positive actuation.

For this purpose, with the ratchets b, which are integral with the digit-bearing 70 drums a, are combined driving pawls c the whole of which constitutes a kind of comb (Fig. 2). These pawls c are pivoted on a common axis d carried by an operating fork e which is pivoted by means of the 75 axis n on the platen of the apparatus. This fork e carries the springs f which act on the pawls c and it is extended in a lug g on which acts a plunger h. This plunger h is arranged in a boss i of the casing; it 80 is subjected to the driving action of a spring such as m and its stroke is limited in any suitable manner.

The pawls c, which are guided by the plate k also carried by the operating fork 85 e, located between the drums a are combined as indicated with the corresponding ratchets b. One tooth of each ratchet is removed (Fig. 1) so that, without interfering with the positive actuation of the drums a, the 90 automatic zero setting pawls c do not actuate them when the parts have resumed their initial starting positions.

In these conditions, it suffices in order to 95 set the parts at zero, to act by successive pressures on the plunger h controlling the comb. Each of the pawls c actuates the ratchet b corresponding thereto for driving the digit-bearing drum a and the angular displacements stopping automatically and independently from each other when the pawl c falls in the interval l which corresponds to the tooth portion which is missing. The movement is stopped when the zero points of all the drums a are in alignment.

What I claim as my invention and desire to secure by Letters Patent is:

1. A zero setting device for registers including a shaft, a plurality of digit bearing drums mounted on said shaft, a ratchet ar- 110

2
ranged within each drum and rigidly attached to the succeeding drum, one of the teeth of each of said ratchets being removed, pawls for cooperating with the 5 mutilated portion of each of said ratchets, a common pivotal axis for said pawls, a forked-shaped lever pivotally mounted on the base of the register and carrying between its arms the common axis of the 10 pawls, and means for oscillating said lever.

2. A zero setting device for registers including a shaft, a plurality of digit bearing drums on said shaft, a plurality of ratchets mounted on the shaft and each having one 15 of their teeth removed, each of the ratchets being arranged within one of the drums and rigidly attached to the adjacent drum, pawls for cooperating with the mutilated parts of the ratchets, a common shaft for rigidly 20 supporting said pawls, a lever in the form of a fork having the pawl supporting shaft

journalled in the arms thereof and pivoted on the base of the register, a slotted vertical guide on the base of the register for slidably receiving the tail portion of the lever, a 25 plunger arranged in the guide for acting on the lever and a spring within the guide for yieldingly supporting said lever, substantially as and for the purposes set forth. 30

3. A device as claimed in claim 2 where-
in a plate is mounted between the arms and
on the forked portion of the lever and is
provided with notches for guiding the
pawls and plate springs secured to the
undersurface of the lever and having the
free ends arranged adjacent the notches and
bearing against the adjacent ends of the
pawls, substantially as and for the purposes
set forth. 35

In testimony whereof I have signed my 40
name to this specification.

CHARLES TORRES WEYMAN.
